James Simpson, Baltimore Maryland

Letters Patent.

The schedule referred to in these Letters Patent, and making part of the same, containing a description, in the words of the said James Simpson, himself, of his improvement, in the application of horse or other animal power for propelling carriages on Railways or Roads.—

To all to whom these presents shall come. Be it known that James Simpson of the City and County of Baltimore & State of Maryland have invented a new & useful improvement in the application of horse or other animal power for propelling carriages on Railways or roads, which improvement consists in this, that the horse or other animal travels and rides at the same time on the carriage which by this power is moved, & any degree of velocity can be imparted to the carriage, which never tires by a steady but moderate movement of the animal which of course enables him to perform a greater length of time under any speed of the carriage, than he otherwise possibly could if its rate of speed depended, as it ordinarily does, entirely on the degree of activity of the animal. To gain this great desideratum the construction or make of the machine or carriage must be as follows, viz; There must be two main shafts or axles of sufficient size and strength of iron or other materials, with four wheels fitted to run loose, & at close or said shafts at such distance as will fit the rails of the road on which they are intended to run, there is to be fixed fast on said axle, a nut or other fixture on the outside of said wheels, to prevent them from running off of the shafts, to which nut or fixture, is centred a dog, fall, or catch on a centre or pin against which a spring acts or pushes outwards sufficiently to throw said fall catch

J. A. Follett

catch or dog into notched teeth fixed on the side of the hub of said wheel next to the felloe, by which means when the shafts are turned round by the power of the animal, one end of said fork being fast to the shaft, thro' the intervention of the nut or other fixture, the other end set against the teeth of the catch wheel, or will cause the road wheel to revolve as fast as the shaft; at the same time in passing a curve in the railway, the wheel on the outer circle is at liberty to revolve faster than the shaft or the wheel on the inner circle of the rail; hence the wheels are always at liberty to advance, but cannot recede without turning the shaft with them; said forks or hatched teeth may also be placed on the inside of the wheels if more convenient so. Furthermore, four fast pulleys or drums are to be fixed upon said axles within the road wheels at such a distance as to bring them directly under the animal's feet, & sufficiently thick or wide to receive bands six to twelve inches wide or any other width; & of such diameter compared to that of the road wheels as will produce any rate of speed, desired. On these bands is to be laid a floor, each plank or board of which is to extend across & beyond the bands on both sides six inches more or less & fastened by iron bolts, with thin wide or heads in the range of the bolt heads, or directly under them or grooves need be turned in the drums or pulleys for the admission of the heads of said bolts, so that they may not run them bands from the drums as they revolve round them; the bolts are to extend about half an inch more or less into the bands or planks above said bands, with a nut to be screwed down close into a slot or hole large enough for said nut to turn in; and after being forced down tight with a wrench, a plug is to be driven in tight over it to prevent its coming off, and the animal's feet from touching it; said bands are to be then entirely covered with boards or planks laid across one foot wide more or less, each having two iron bolts in the middle

middle of them fall on a line with each other, by reason of which they will pass round the animals without varying the tightness of the bands & without any liability of splitting the bands or planks, which may also be fastened to the bands by wood screws, nails or other means in like manner. The two main axles on which the bands and floor revolve must be at a distance sufficient to prevent the animals feet from extending beyond them either either way. The two on the bands on the main axle, must be placed one on a double row of pulleys & one on each shaft near the outer ends, & directly under the horses or animals feet, and bands in a line with those on the main axle. The upper or peripheries of which must be at a horizontal with those or such a little below, & as near to each other as they can be without touching for the support of the revolving & flexible floor, & which will effectually prevent the floor from sinking beneath the tread of the animals feet. If two rows of pulleys or drums under each band be used, the outside rows should extend to the outer edges of the bands & before increasing thick if for ten inch bands, & lie as near to each other as they can, leaving a sufficient space for the shaft of the inside rows to pass between the peripheries of the outside rows without touching. The pulleys of the inside rows should be six inches thick, being so turned that they shall just clear the inside of the outside pulleys or drums, those two next to the main axles should be lagged in the middle reaching to, but not quite touching the inside of those on the main shafts, or axles, raised no much above those on each side, as the thickness of the bands, by which means they will receive & support the floor, when it revolves past the first entailing or hollow of the outside drums. The centres of all the middle or outside pulleys should rest on friction wheels, either one, two or three, if one wheel only there must be a slot in the nail to support the shaft, about 6 or 7 or 8 inches, they must lay side by side with regard to

here

line, their centers sufficiently distant to let each upon the peripheries of the others without touching, in which position they leave a place for the pulley shafts to rest in without other supports, and thirdly, if on three rollers, two must be fixed in the frame or side of said carriage, one on each side of the shafts of the pulleys, and the third directly underneath it on which the pulley shaft is to revolve and bear its whole weight, or the pulleys may rest on their own bearings, without any fiction rollers whatever. A frame of sufficient height, length & width is to be made to receive the animal or animals &c. and of sufficient depth to receive the friction wheels of the pulleys under the floor boards, & a part of the sides, at least must be durable to support the centers of eight other friction wheels (but if the machine is made without any fiction wheels, there must be two main timbers running short & extending beyond the wheels each way for their protection; & also in this particular for that with friction wheels) their under edges will be above and rest upon the boxes of the main wheels of the road wheels; the side posts must go down sufficiently below these side timbers or rails to receive a platform, on which must be placed two rails laying parallel to each other & reaching nearly from one axle to the other, & of sufficient width & thickness to sustain the pulley shafts under the floor boards enthrone the weight of the pulleys & animals rest. The eight friction wheels are for the whole frame to rest upon, & their under peripheries move with and upon the axles of the first described road wheels said friction wheels may be of any dimensions in diameter or thickness, which may be found most convenient to use with their centers as before described in the second proportion or the carriage may rest upon boxes without any fiction wheels whatever. The road wheels are made to revolve by the horse or other animals moving at any rate of speed, upon the revolving floor, the car must also be made and never be out

end of said main axle and another friction wheel, located in the frame of the carriage to sustain them in their places under the weight of the floor bands, also to keep the axle in the centers of the castings of the eight friction wheels on which the carriage rests. These friction wheels will always keep the two axle on a parallel line with each other but will admit the shaft or axle to be forced forward by the bands being loose by a guide running on the road before the carriage for that purpose or otherwise to turn on any curve in the road that is to say, neither end of the forward axle can recede or move back by reason of the friction wheel behind, but may advance, so likewise the after axle cannot be moved forward, for the centers of the friction wheels being fixed in the frame directly before, permit it, but it can be moved backward so as to conform to the forward axle in turning a curve in the road. All the friction wheels are to be made of a thickup, conformable to the magnitude of the weight they are intended to support, of a diameter as extended as the nature of their application will conveniently admit, & their centers must always conform in length & diameter to the tension of gravity in all cases applicable to their intended uses. It is also intended in case roads or railways are not entirely level, or horizontal throughout, but have places of inclines to construct the tow carriage as to enable the same animals to take up the inclines as much as they can draw or travel at an advanced speed by means of a reduction of the speed of the tow carriage conformably to the amount of gravity of the incline which it is necessary to ascend. At the summit the speed is again renewed, the resistance being lessened, or the speed of the carriage is again in unison with that of the animals as a first graduated. This object is accomplished thus, The driver or pulley on the main axle over which the bands or chain floors revolve, is to be fitted on the shaft to run with composition or iron boxes, inside of these pulleys or drivers of cast iron or dog iron is to be fixed to the shaft. Then

a bayonet is to be fitted onto said shaft, the fork of which is to pass the said pulley, and come in contact with the fast arm or dog on the shaft, & will then cause the pulley to be fast or a fixture to the main shaft, of course once again to turn without the other, but by sliding out the bayonet the fork lose their hold and then all the drums become sufficiently loose to revolve upon the main shaft of the carriage, by doing which all motion of the carriage ceases, as the floor or floor on which the animals travel revolve round without causing the shafts to revolve but for a small bevel or spur pinion which is fixed on the outer side or edge of the bayonet hub being made to come into gear at the same time the fork leave the fast dog on the inside of the pulley or drum, and the drum is thereby free from the carriage or shaft, to communicate any other speed or motion to the carriage which is wanted, or the following other application of gears will do, with a small bevel or spur gear fixed upon a small shaft, laying perpendicular between the floor and road wheels, reaching if necessary to the other axle, on which shaft is also a sliding wheel or spur gear made to come in contact with a gear or made fast to the inside of the road wheels, & on said wheels so fastened to the road wheels may be one, two, three or four rows of teeth, more or less, on circles one without the other, so that in whichever line or row of teeth the small side gear is made to come in contact with, the speed of the carriage will conform to, for instance, if the gear on the face of the bayonet hub, having teeth on it, and the small gear on the shaft parallel to the floor has ten, in all these there is no gain or loss of speed, but the last mentioned side gear being made to come in contact with the outer row of teeth on the road wheels which now we will say has forty teeth on it, it will reduce the speed of the carriage to the actual speed of the animal, at the previous speed.

speed of the carriage in a given time of pull. The aforesaid small gear shaft must be centred in two studs or boxes which must be fastened to a frame by itself & that again be attached to the main frame of the carriage so as to allow it to move forward & back by means of a flock. Shifting the main shaft connected to the frame so that when the main shaft is moved to conform to the curves of the road, the gears will all maintain their relative bearings & connections with each other, but this is only necessary when the animals are allowed to vibrate to the curves of the road; if it is necessary to convey the power of the animals to all the road wheels, it may be done by a pulley projecting from the pulley under the main board, fast to it on the opposite side of the above gear, with a band passing over it to a pulley of the same size, made fast to the road wheel on the other axle.

What I claim in the before mentioned carriage as my invention or improvement is its application to horses or other animal power, whereby he or they can travel fast upon said carriage either upon roads or railways, & by so doing impart a power to move said carriage either with accelerated or diminished speed, compared with that of the actual travel of said animals. I also claim the invention of the application of friction wheels to sustain the weight of said animals & the weight of the pulleys under the flexible floor; & the double rows of pulleys or drums under each hand. Also the application of friction wheels to support the weight of the frame, animals, apparatus, & load, connected with, & about said frame said carriage being of itself a new & useful improvement, over locomotive carriage before unknown or used. I also claim the application of the gear principle whereby a variation of the speed of the carriage more or less is effected without varying that of the animals as herein before recited.
